(54) **BENCH, PERPETUAL SHOE**

(76) Inventor: **Samuel Haynes**

Samuel Haynes
Dittoe Patent

The Schedule referred to in these Dittoe Patent and making part of the same, containing a description in the words of the said Samuel Haynes himself of his improvement in the art of Manufacturing Boots and Shoes which he calls "The perpetual Shoe Bench."

To all persons to whom these presents shall come
Samuel Haynes of Melton in County of Middlesex and State of Massachusetts, Manufacturer of Boots and Shoes sends greeting. Be it known, that I, the said Samuel Haynes have invented, constructed, made and applied to use a new and useful improvement in the art of Manufacturing Boots and Shoes which I call "The perpetual shoe Bench." My said invention or improvement is plainly and fully described and described in the words and figures following, to wit: My Bench and any part of it may be made of Mahogany, oak or any other wood, or of iron or any other metal. My Benches are about three feet high, or they may be made of any other height to suit the taste of the operator. The lower part of the Bench is a plank or other platform as is represented by the letter A, drawing No. 1 of the width of about three feet, and of the desired length of the Bench. It lies on the floor of the workshop and must be sufficient thickness to receive and hold firmly the standards, shafts, uprights that procure from it to support the upper platform or working Bench B. B. B. are the standards, shafts or uprights standing at right angles on the lower platform on the centre of it extending, to one third of its width, well secured to and through it about four inches in width and proceeding upright from the lower platform up to and through the upper platform or working Bench grooved in the front as a back part in that portion of it that rises above the working bench, in a convenient manner to receive and hold firm the heel and toe part of the shoe. The centre parts of these standards, shafts or uprights are to a convenient distance below the working bench cut down so that the shoe may be attached to the shoe and play easily and freely. C, C, C, is the upper platform or working Bench. It is about two inches thick in my apparatus and proceeds from the front side of the standard, shaft or uprights back to a line concur with the

the back side of the lower platform. Through this or notches or slots of suitable dimensions, the standards proceed and are well secured therein. A, is a board descending 6 or 8 inches from the front side of the working bench and on the front sides or edges of the uprights or standards are securely fastened to the front side of the working bench, and to the uprights. B, is a ledge on the back side of the working bench two or three inches high made merely for the convenience of the operator to prevent his tools & materials from falling off on the opposite side. D,D,D, &c are the shoes or boots placed on the grooves of the uprights and arranged at a convenient distance above the working bench for the operator. C,C,C, &c are leather straps attached at the upper end to the projecting parts of the lasts by hooks inserted into holes bora through the projecting parts of the lasts, or by passing through loops of leather temporarily fastened to the shoe or boot & last on the instep and hanging down as the shoe is placed & projecting downward far enough for the strap to pass through it. The strap then passes down to and around the bars or levers d,d,d, &c. The bars or levers d,d,d, &c are fastened to the lower platform on the back side by leather or other hinges and on the front side they play up and down at pleasure. e,e,e, &c are catches or flanchises, fastened to the standards or uprights under which the bar, d, is brought at pleasure by the foot of the operator. The strap, c, must be so adjusted that when the front of the bar, d, is brought down it may readily pass under the catch, e, so that the shoe will be held firmly in the grooves of the uprights above the working bench. The uprights and of course the shoe thus firmly secured in the grooves above the working bench are placed one foot apart. The number of the shoes placed on the bench for one operation as represented in the plans and model herewith sent is ten, — but it is obvious that they may be multiplied to any desired number by increasing the length of the bench. Figures or drawings A & B represent the bench and its prominent parts — and the shoes and boots on the lasts with the leather on them fit for operation in different positions which cannot be mistaken by any mechanician on inspecting the drawings. Some parts of the machinery herein before stated and described have been heretofore known and used. I believe some parts of it are new, but not being sure of this, I herein claim no particular part of the machinery as constituting my invention. But my invention which I hereby claim

claim and for the exclusive right to use which I now desire Letters Patent is
a Combination of Machinery to produce a new and useful result. The decided
utility of my invention consists in this. When the bench is prepared with
one or more places for shoes on it, the lasts with the leather placed therein in
its first state for Manufacture should be secured in the grooves. The operator
should then successively stitch the upper leather to the inner soles on all of them
so that the soles should be placed on all the shoes, and the operator should peg
on all the soles successively, and so of the heels, polishing and finishing.
In this mode with my combination of Machinery, by working on many shoes
successively in each part of the Manufacture, and in avoiding the frequent
changes of the materials and the positions of the shoes by the operator, he will
be able in a given time to manufacture and finish, and complete, in a thor-
ough and workman like manner more than double the number of shoes or
boots, that he could finish on the usual modes of Manufacture now in use.
For making boots the front of the standard or upright from below when it passes
through the working bench, must be detached therefrom sufficiently to
let the boot leg descend over it while the boot is in the operation of Manu-
facture.

In testimony that the above is a true specification of my said invention
so improvement I have hereunto set my hand this thirteenth day of August
in the year of Our Lord one thousand eight hundred and thirty four. End
